(57) **CLAIM**

The ornamental design for a welded wye connector, as shown and described.

DESCRIPTION

FIG. 1 is a frontal perspective view of a welded wye connector;

FIG. 2 is a first side elevational view thereof;

FIG. 3 is second side elevational view thereof;

FIG. 4 is a front elevational view thereof;

FIG. 5 is a rear elevational view thereof;

FIG. 6 is a top plan view thereof; and,

FIG. 7 is a bottom plan view thereof.

The broken lines shown in the drawings depict portions of the welded wye connector that form no part of the claim.
